(57) **CLAIM**

The original design for an industrial protection helmet with
headband adjusted by pins, as shown and described.

DESCRIPTION

FIG. 1 is a front view of the industrial protection helmet with
headband adjusted by pins;

FIG. 2 is a rear view thereof;

FIG. 3 is a right side view thereof;

FIG. 4 is a left side view thereof;

FIG. 5 is a top view thereof; and,

FIG. 6 is a bottom view thereof.

The broken line showing the underside interior is included
for the purpose of illustrating a portion of the helmet that
forms no part of the claimed design.
